UNITED STATES PATENT OFFICE

164,759

ELECTRIC MASSAGER FOR THE HUMAN BODY

Edgar O. Bartolucci, Union City, N. J., assignor of one-half to John J. Waldheim, Chicago, Ill.

Application March 20, 1950, Serial No. 8,636

Term of patent 14 years

(Cl. D83—1)

To all whom it may concern:

Be it known that I, Edgar O. Bartolucci, a citizen of the United States, residing at Union City, State of New Jersey, have invented a new, original, and ornamental Design for an Electric Massager for the Human Body, of which the following is a specification, reference being had to the accompanying drawing, forming a part hereof.

Figure 1 is a perspective view of an electric massager for the human body showing my new design;

Figure 2 is a top plan view thereof; and

Figure 3 is a side elevational view thereof.

I claim:

The ornamental design for an electric massager for the human body, as shown.

EDGAR O. BARTOLUCCI.
